UNITED STATES PATENT OFFICE.

HENRY B. SLATER, OF RIVERSIDE, CALIFORNIA.

ELECTROLYTIC PRODUCTION OF HYPOCHLORITE SOLUTIONS.

1,397,239.

Specification of Letters Patent. Patented Nov. 15, 1921.

Application filed November 9, 1920. Serial No. 422,826.

To all whom it may concern:

Be it known that I, HENRY B. SLATER, a citizen of the United States of America, residing at Riverside, in the county of Riverside and State of California, have invented certain new and useful Improvements in Electrolytic Production of Hypochlorite Solutions, of which the following is a specification.

10 The present invention relates to the production of hypochlorite solutions, particularly the hypochlorites of the alkali metals, and for the purpose of illustration, the production of sodium hypochlorite solution, 15 suitable for use as a disinfecting solution, will be particularly described herein.

By the employment of the present invention, the production of a hypochlorite solution of high concentration of hypochlorite 20 and low concentration of chlorid can be readily effected, and a product readily meeting the requirements of the test for Dakin's sodium hypochlorite solution can readily be secured.

25 The accompanying drawings show diagrammatically the preferred construction of an electrolytic cell for employment in accordance with the present invention. In said drawings, Figure 1 shows a vertical sectional elevation of the preferred construction of the cell. Fig. 2 shows a plan section, taken approximately on the line 2-2 of Fig. 1 looking downwardly and Fig. 3 is a side view of one of the electrodes. 30 Fig. 4 is a central vertical section and Fig. 5 a top plan view of modified form of apparatus for carrying out the production of hypochlorite solution according to the present invention.

40 Assuming that sodium chlorid is to be treated, this solution enters by the pipe 1, and by means of the valve 2 is allowed to flow through pipe 3 (the connection between pipe 1 and pipe 4 being closed by said 45 valve 2) the solution thereby entering the cell 5 through the pipe 6, which may terminate, as shown, at a point near the bottom of said cell. In starting the operation, the air in the cell 5 will first be expelled to 50 waste through pipe 7, the valve therein being open for this purpose. The liquor will eventually fill the cell 5, whereupon the valve in pipe 8 will be opened and the pole changer 9 will be thrown into the position

illustrated, whereby connection is made 55 from the positive terminal to the upper end of the electrode 10 which will thereby become the anode of the cell and an electrical connection will be made from the negative terminal to the upper part of the electrode 60 11, whereby the electrode 11 becomes the cathode. 10 and 11 may be made of graphite, if desired. The liquor is allowed to flow continuously through pipe 1, valve 2, pipe 3, inlet 6, through the perforations 12 in the 65 cathode, through the perforations 13 in the anode and out through pipe 8, the valves 2 and 14 being suitably adjusted to maintain the flow while maintaining the cell 70 full or approximately full of the electrolyte. 75 It will be observed that by this mode of procedure the sodium is liberated at the cathode 11, which quickly unites with water to form caustic soda, and this caustic soda flows toward the right in Fig. 1, into contact with the anode, whereby an excess of sodium hydroxid solution is maintained in contact 80 with the anode so as to instantaneously absorb the chlorin liberated at the anode and the hypochlorite solution then flows off 85 through pipe 8 without having any substantial portion of the hypochlorite converted into chlorate. The connections are maintained as above indicated until such time as the impurities in the original brine em- 90 ployed have, to some extent, been precipitated upon the electrodes, which action, if continued, would decrease the efficiency of the cell. The valve 2 is then changed, to close the connection between pipes 1 and 3 95 and to open the connection between pipes 1 and 4, the valve 14 is closed and the valve 15 is opened, whereby the liquid will flow through pipes 1 and 4 into the right-hand compartment of the cell through the perforations 13 and 12, and out through the valve 15. The pole changer 9 is then swung into the opposite position, whereby 11 becomes the anode and 10 the cathode. The first portions of the liquid thus flowing in 100 the opposite direction will carry substantially the entire amount of accumulated precipitated matter, leaving the electrodes clean.

During the operation, practically none of 105 the chlorin liberated will rise to the surface of the liquor in the cell, the chlorin being absorbed quantitatively and substan-

tially instantaneously by the caustic soda solution. The hydrogen liberated at the cathode never comes into contact with the hypochlorite solution, and will accordingly 5 quickly rise to the surface and will be drawn off through the pipe 7.

The inlets and outlets for the liquor are preferably placed, as illustrated, at or near the bottom of the cell, whereby the cell can 10 easily be cleaned. Another advantage in locating the inlets and outlets at near the bottom of the cell is that the liquor in the vicinity of the anode is maintained at a low temperature, this being conducive to high 15 efficiency of production and also this reduces the tendency to the formation of chlorate.

On account of the fact that the hydrogen is evolved entirely out of contact with the 20 hypochlorite solution, there is substantially no reduction of hypochlorite by the nascent hydrogen produced, hence the liquid is not heated up and the production of chlorate from hypochlorite is reduced to a minimum.

25 In some instances it might be advisable to omit the cover 16 of the cell and to allow the hydrogen gas to pass to waste. Ordinarily, however, it is advisable to provide a cover and to draw off this hydrogen through 30 pipe 7 for use for any desired purposes.

The cell is particularly useful in connection with the production of hypochlorite from common salt which material frequently contains small quantities of magnesium 35 salts, calcium salts, etc., which metals are liable to be deposited as hydroxids on the cathode. By reversal of the direction of the current and by reversal of the direction of the solution, in a short time the precipitated 40 hydroxids will either be converted into soluble compounds or will be readily loosened from the surface of the electrode and will flow out with the solution within a very short time after reversal of the flow.

45 A modified form of execution of the process within the scope of the present invention may be carried on with an apparatus shown in Figs. 4 and 5, Fig. 4 being a central vertical section (partly in elevation) and Fig. 50 5 being a top plan view, of such modified form of apparatus.

In the apparatus shown in Figs. 4 and 5, 20 is a cylindrical receptacle which may be open at the top and which contains centrally 55 located therein a vertical tubular perforated anode 21. The cell is provided with suitable cathodes for example a lining 22 of graphite or in some instances, metal. Also if desired, suitable metallic vertical cathodes could be 60 employed. The brine is fed in through a pipe 23, at the top of the cell, a suitable valve being provided in this pipe for controlling the flow of the brine. The pipe 21 which is perforated with numerous small 65 holes 24 at various points in its height is

continued downwardly through the bottom 25, which may be conveniently made of an insulating material, suitable plates 26 and 27 being provided for supporting the insulation 25. The pipe 28 which forms a continuation 70 of the pipe 21, below the bottom of the cell, is provided with a suitable valve 29 for controlling the out-flow of hypochlorite solution from the cell.

In the form of apparatus shown in Figs. 75 4 and 5, the cell itself can be constructed of graphite instead of merely having a lining 22 of graphite. In this case a convenient mode of attaching the cathode to the current supply would be a strap or belt of metal 80 surrounding the cell, either at its top or bottom or some intermediate point.

The anode 21 may likewise consist of graphite, and may be connected to the source of electricity by a metallic ring 30 surrounding the anode 21, for example at its top. If desired, the electrical connection could 85 also be made to the pipe 28.

I claim:

1. A process of making hypochlorite solution, which comprises passing a solution consisting essentially of an alkali metal chlorid through an electrolytic cell, and causing the liquor to flow from the cathode toward and 90 into contact with the anode.

2. In the electrolysis of salt brine, the step of passing the brine in contact with the cathode, then into contact with the anode and through perforations therein, whereby chlorin given off at the anode is set free in 100 the presence of free caustic soda and then passing the solution out of the cell, immediately after passing through the perforations in the anode, whereby contamination of the solution is minimized.

3. A process of continuously producing hypochlorite solution which comprises passing a solution consisting essentially of water and an alkali metal chlorid, and containing some impurities, through an electrolytic 110 cell, by introducing the said solution in the vicinity of the cathode, and allowing the same to flow in contact with such cathode, then toward and into contact with the anode and then out of the cell, and when insoluble 115 impurities have been deposited upon one of said electrodes, reversing both the polarity of the electrodes and the direction of flow of the liquor through the cell.

4. The process of producing hypochlorite 120 solution by passing a solution consisting largely of alkali metal chlorid through an electrolytic cell, first in contact with the cathode and thereafter in contact with the anode, whereby any precipitation of impurities in the alkali metal chlorid solution is produced largely in the vicinity of the cathode, the liquor being introduced at near the bottom of the cell and also being withdrawn 125 at near the bottom of the cell.

5. An electrolytic cell comprising a container, an anode and a cathode therein, a liquor inlet to each end of said cell, a liquor outlet from each end of the said cell, and a pole-changer in the electrical connections leading to said electrodes.

6. An electrolytic cell comprising a container, a cathode and an anode, means for

introducing liquor to be treated in proximity to said cathode and means for withdrawing liquor from said cell, in the vicinity of said anode, whereby liquor is caused to flow toward said anode and away from said cathode.

In testimony whereof I affix my signature.

HENRY B. SLATER.
